WATER SOFTENING SYSTEM VALVE

Ralph D. Zimmerman, Omaha, Nebr.

Application December 10, 1946, Serial No. 715,250

3 Claims. (Cl. 251—54)

1

The present invention relates to the water softening art and more particularly to valves used in conjunction with water softening systems.

In the prior practice of the art, five or more separate valves have been employed for consummating purposes for which the single valve mechanism of the instant invention may be employed, whereby in the prior practice the labor and time required for opening and closing valves has been lost.

Also as heretofore practiced it has often happened that an operator would open the wrong valve, whereby brine was distributed in lieu of softened water, and the present invention aims to obviate several objectionable features of the prior practice and to provide a device which employs fewer parts than heretofore.

It is an object of the invention to provide a valve usable for consummating water-softening resultants in a more facile, economical and advantageous manner than heretofore.

Another object of the invention is to provide a valve which is so constructed and the parts thereof so cooperatively arranged with respect to each other that debris, fine sand and similar abrasive material carried by water does not detrimentally affect the operation thereof.

A further object of the invention is to provide a valve mechanism which becomes flushed out resultant from use, whereby repairs and adjustments are not required during a comparatively lengthy period of use.

A still further object of the invention is to provide a valve mechanism for the above stated purposes which operates to obtain selected results responsive to an operator positioning a lever handle thereof in a position complementary thereto.

Other and further objects of the invention will be obvious from the following detailed description.

In the drawings:

Figure 1 is a top plan view of a valve embodying the preferred construction of the new mechanism.

Figure 2 is a front view thereof.

Figure 3 is a side view of the new valve.

Figure 4 is a longitudinal section, the view being taken substantially on line 4—4 of Figure 2.

Figure 5 is a plan view of the interior face of the A portion of the valve at the time the B portion or housing is removed therefrom.

Figure 6 is a plan view of the exterior face of the portion A of the new valve.

Figures 7, 8 and 9 are transverse sectional

2

views of the A portion of the valve, said sections being taken respectively on lines 7—7, 8—8, and 9—9 of Figure 6 and looking in the direction of the arrows.

5 Figure 10 is a longitudinal section taken substantially on line 10—10 of Figure 4.

Figure 11 is a similar section taken substantially on line 11—11 of Figure 4.

10 Figure 12 is a transverse section, the view being taken substantially on line 12—12 of Figure 4; and also on line 12—12 of Figure 3, the depiction being turned at an angle of 90 degrees with respect to Figure 3.

15 The valve of the present invention is particularly useful in conjunction with a water-softening system which employs "Zeolite" crystals in a tank thereof. The said "Zeolite" system includes two tanks, one of which is known in the vernacular of the art as the brine tank, being provided with a conventional cut-off valve, and the other is known as the water-softening tank since it contains the "Zeolite" crystals which soften the water.

20 The valve of the present invention includes two primary portions, which are a conduit-containing portion or valve body indicated at A in the drawings and a valve-cage or bonnet portion B. The portions A and B are secured together preferably by means of bolts C so that the surface 10 of the portion A confronts the surface 11 of the portion B and, during use, the portion B of the valve is preferably so disposed that it confronts an operator, having its major axis disposed in a horizontal direction, whereby its lever handle is disposed vertically for facilitating manipulation.

25 As best shown in Figure 4, the portion B, being concave, provides a cage or housing for certain later described mechanism employed for imparting a shift-slide motion to the valve-head of the new valve. The portion B includes a wall 11 which is of a substantially oval shape in plan as shown in Figure 11. The valve of the present invention further preferably includes a gasket 12 which is disposed between the surface of the wall 11 of the portion B and a confronting surface 10 of the portion A, said gasket 12 being also approximately oval in plan complementary to the oval shape of the wall 11.

30 The gasket 12 is preferably formed of compressible material such as rubberized canvas or a suitable one of the slightly resilient modern plastics, whereby at the time the portions A and B are joined together by means of the bolts C, a water-tight chamber 14 is provided by the in-

terior of the portion B in conjunction with the plane surface 10 of the portion A.

The surface 10 of the portion A, as best shown in Figure 10, is provided with an intake passageway 13 the wall of which is provided with a screw thread for connecting one end of a pipe 13' thereto. The pipe 13' is represented by dotted lines in Figure 4. The passageway 13 extends through the portion A at a right angle with respect to the length of the portion A.

The other end of the pipe 13' is in communication with a source of supply of water under pressure, the said supply being known, to those skilled in the art, as raw water, namely, water which has not been softened; and the said raw water is introduced into the chamber 14 of the valve of the present invention through the passageway 13. The latter is shown in full lines in Figure 9.

Referring to Figure 10, the portion A is provided with five ports or ends of passageways which extend inwardly thereof from the surface 10, said ports being indicated at 15, 16, 17, 18, and 19, respectively. The ports 15 to 19, inclusive, are each of the same size and contour in plan, being elongated transversely of the portion A, disposed in a row and spaced apart equidistantly with respect to each other.

During use certain of the ports 15 to 19, inclusive, are, at times, in communication with the chamber 14 and at other times are cut off from direct communication therewith by means of a later described slidable valve-head which is also shiftable away from the portion A by means of a later described mechanism.

The port 15 is in communication with a passageway 20, as best shown in Figure 4. The passageway 20 is threadedly connected to one end of a pipe 21 during use. The pipe 21 is employed for distributing softened water for use in a dwelling or commercial institution such as a laundry or the like, said pipe 21 being usually called the "service line."

The port 15 is also employed, at times, as a by-pass for hard or raw water during times when the valve of the instant invention is manipulated for regeneration purposes; namely, a regeneration of the conventional "Zeolite" crystals, the latter being employed in a water-softening system for softening water in a well known manner; it being also well known that the said crystals require periodical regeneration.

The port 16 is in communication with a passageway 22 provided in the portion A of the valve. A portion of the passageway 22 is shown in full lines in Figure 4 and is represented by dotted lines in Figures 6 and 10. The passageway 22 is in communication with a pipe 23, and the latter extends to a tank, not shown, of the said conventional "Zeolite" water-softening system.

The port 17 is employed for draining off debris during a back-washing operation applied to the said tank of the said system, and for this purpose water under pressure passes through the port 17 as later described.

As best shown in Figure 4, the port 19 is in communication with a passageway 24 provided in the portion A of the new valve. The passageway 24 is in communication with the port 18 at all times through a passageway 28, since the latter is in communication at all times with the passageway 24 through a restricted opening 25, the latter being provided through an injector or suction applicator 26. The member 26 is cup shape in cross section. Since the bore of the

opening 25 is of a lesser cross sectional area than the cross sectional area of a pipe-receiving opening 82', a Ventura-tube-like action is provided for applying a suction for causing a liquid brine to enter the passageway 28 through the opening 82' as later described. The opening 82' is provided with a screw thread for engagement with one end of a brine pipe 82, whereby brine is introduced into and through the new valve from the brine tank of the said water-softening system.

The portion A is provided with a passageway 32 one end of which is in communication with the medial port 17. The other and threaded end 33' of the passageway 32 is threadedly attached to a pipe 33. The latter is represented by dotted lines in Figures 1, 3 and 4, and extends to a sump having a connection with a sewer whereby liquid passing through the new valve may be drained to the sewer through the pipe 33 and at times when it is desired to dispose of the drainage as later described.

The brine tank and its use, together with the several other parts of the said system, being well known in the art, is not believed to require a detailed description.

As best shown in Figure 4, the injector or suction applicator 26 fits snugly into the bore adjacent the flared or expanded end of the passageway 24 and may be disposed to cover more or less of the opening 82' and the pipe 82 for permitting a greater or lesser flow of brine through the pipe 82 as may be desired. The member 26 is positioned within the A portion of the valve structure through an opening 29. The wall of the opening 29, as best shown in Figure 4, is provided with a thread for securing a pipe plug 30 thereto, and preferably a gasket 31 is employed for sealing the opening 29 against an escape of water under pressure through the opening 29.

As shown in Figure 12, the portion A of the valve is provided with an orifice 35 having screw threads on the wall thereof for attaching one end of a pipe 36 thereto, whereby the latter is in communication with a passageway 37 of the portion A of the new valve. The other end of the pipe 36 extends to the top of the water-softening tank of the system. The passageway 37 extends to and is in communication with the port 18, as best shown by dotted lines in Figures 6 and 10.

Within the chamber 14 of the new valve, a valve-head 41 is slidably and shiftably disposed. The surface 42 of the valve-head is machined smooth and provided with a recess 43, the mouth of the latter being disposed inwardly of the valve-head from the surface 42 thereof, as best shown in Figures 4 and 11.

The surface 42 of the valve-head is provided with an apertured filler-pad 42', the latter being formed of the said suitable resilient material. Preferably the compressible pad 42' is of approximately the same thickness as the gasket 12 when in a sealing position. The pad 42' is secured to the surface 42 of the valve-head 41 by any suitable means such as by an employment of cementitious material, screws or the like suitable keepers, not shown, and about the mouth of the recess 43. The walls of the aperture of the pad are disposed in alignment with the side walls of the recess 42 of the valve-head. The oppositely disposed side walls of the recess 42 which are shown in Figure 4 are spaced apart a sufficient distance so that said side walls span over

any selected next adjacent two of the ports 15 to 17 for transferring a liquid from one of the selected ports or passageway ends to another end.

During use the ports 18 and 19 are not coupled together through the recess of the valve-head 41 at any time although, at times, the valve-head is employed for plugging the port 18, as shown in Figure 4.

Within the chamber 14 two spaced apart like guide posts 44 and 45 are provided. The posts are provided with threaded ends which are threadedly attached to the portion A of the valve, as shown in Figure 4.

A guide plate or track member 46 is provided having an elongated guide sleeve 47 at one end thereof and a like guide sleeve at its other end. The guide posts extend through the sleeve guides 47 respectively, whereby the guide plate 46 is shiftably disposed on the posts, toward or away from the surface 10 of the portion A of the valve, by a later described means. The free ends of the guide posts are each provided with a detent pin 48 for their respective washers 49. Between the washers and the plate 46, expansion springs 50 are provided. The springs are disposed about the posts respectively for normally urging the guide plate and the valve-head attached thereto toward the portion A of the valve.

The valve further includes a longitudinally slidable shaft 51. The shaft extends through a packing nut 52 and a stuffing box 53. The latter contains packing for preventing a leakage of water under pressure outwardly of the valve cage or chamber 14. The pack nut 52 is threadedly secured to the stuffing box nut 54 and the latter is similarly threadedly attached to the adjacent wall of the chamber 14, as best shown in Figure 4.

The nut portion 55 of the stuffing box extends beyond said box. Between the nut portion and the adjacent machined outer surface of the portion B, a ring 56 is rotatably disposed. The ring provides a mounting for later described ears and an attached link.

That end of the shaft 51 which is disposed within the chamber 14 is provided with a detent washer 57. The latter is secured to the shaft by means of a keeper pin 58.

A similar pin 59 is employed for attaching a mutilated spur wheel 60 to the shaft 51. As best shown in Figure 5, the teeth of the spur wheel are arranged to successively engage the teeth of a rack bar 61 during revoluble movement of the shaft 51 and the spur wheel. The guide plate 46 is disposed between the spur wheel 60 and the detent washer 57.

As best shown in Figure 12, the rack bar 61 is formed integral with an arm portion 62 of the valve-head 41 for carrying the inwardly disposed rack bar portion of the arm 62.

An arm 62 is also attached to the valve-head 51, being oppositely disposed with respect to the arm 62. The free end of said arm 63 is provided with an inwardly disposed flange portion or track following member 64. The arms 62 and 63 are spaced apart a distance approximately equal to the transverse width of the guide plate 46, whereby the valve-head is slidable longitudinally with respect to and guided by the plate 46.

At times when the shaft 51 is moved in the direction of the arrow 65 (Figure 12), a corresponding movement is applied to the guide plate 46 for causing the flange 64, together with the rack bar 61, to shift the valve-head 41 away from the portion A of the valve and against the urge of the springs 50 for protecting the filler pad

42' against abrasive contact with the edges of the ports 15 through 18 during a sliding movement of the valve-head longitudinally of the guide plate 46.

It will be seen that the rack bar 61 also functions as a tract following member in cooperation with the portions or members 64 for slidably securing the head 41 to the track or guide member 46.

As shown in Figure 4, the outwardly disposed end of the shaft 51 is provided with a flat end portion 66 through which a pin 67 is disposed. As best shown in Figure 12, the pin 67 also extends through a lever 68.

Referring to Figure 2, the lever 68 is formed integral with its handle portion 69, the latter preferably being offset with respect to the lever as best shown in Figure 3.

Referring to Figure 12, the end of the lever which is opposite to its handle is provided with a further pin 70 for pivotally attaching one end of a link 71 thereto. The other end of the link is pivotally attached by means of a pin 72 to and between oppositely disposed outstanding ears 73. The latter are secured to the above mentioned rotatable ring 56, as best shown in Figures 2 and 12.

The handle 69 may be manipulated for causing the shaft 51 to rotate, since the ring 56 rotates correspondingly, for causing a corresponding movement to be applied to the mutilated spur wheel 60, whereby a resultant sliding movement is applied to the rack bar 61 and to the valve-head 41.

Before the shaft 51 is caused to rotate, as above described, the valve-head is first lifted or shifted away from the portion A of the valve, whereby the filler pad 42' of the valve-head is prevented from becoming rubbed or abraded during a sliding movement of the valve-head in parallelism with the surface 10 of the portion A of the valve. During use of the valve, debris and sometimes fine sand and other abrasive material which is carried by the water of numerous communities, becomes flushed outwardly of the new valve; and by means of the specific construction and cooperative arrangement of the parts of the new valve, the latter operates efficiently even in the event that a grain of sand becomes temporarily lodged between the pad 42' and the surface 10 of the portion A, since the pad receives said grain when compacted against the surface 10.

Since the valve-head 41 is first shifted away from the portion A and before the valve-head is caused to slide longitudinally of the portion A, undue abrading of the pad 42' is prevented; while at the same time the pad may be seated sufficiently snug to permit repeated operation of the valve efficiently for all practical purposes required during water-softening and tank back-washing uses.

The crank handle 69 is not only movable in the direction of the arrow 74 (Figure 3) for shifting the valve-head, but is also swingable in an arc of approximately 160 degrees for causing the valve-head to slide.

The portion B of the valve is provided with a projection 75 which, as best shown in Figure 2, is approximately semicircular in plan. The terminal arcuate end edge of the projection 75 is provided with detent notches for cooperation with the lever 68.

Referring to Figure 2, three notches are indicated at 76, 77 and 78, respectively. The notches are provided on the said terminal edge portion of the projection 75 for receiving the restricted portion 79 of the lever 68 in any selected one

thereof for causing the lever to be correspondingly positioned at times when the side walls of a selected notch engage the lever portion 79.

The valve-head 41 may be caused to shift and move away from the portion A as heretofore described, whereupon the lever is further manipulated and swung to cause the valve-head to slide longitudinally with respect to the guide plate 46.

At the time the valve-head is positioned in any one of the three positions corresponding to a placing of the lever in a selected notch 76, 77, or 78, the recess 43 of the valve-head then spans across a selected two of the ports 15 through 18 for switching a flow of material through the new valve correspondingly.

At times when the valve-head is in the position shown in Figure 4, a communication between the ports 16 and 17 is provided since the recess 43 of the valve-head is then positioned for causing the same, and at this time the lever 68 is engaged in the notch 77.

At times when it is desired to permit a flow of liquid between the ports 17 and 18, the recess 43 of the valve-head is caused to be disposed over the said ports so that the side portion 80 of the valve-head closes or seals the port 19 and at this time the lever 68 is engaged in the notch 78. It will be seen that the side portion 80 is disposed further from the recess 43 of the valve-head than is the oppositely disposed side wall of said head, as shown in Figure 4. As best shown in Figure 11, the major portion of the aperture of the pad 42' is disposed at one side of the transverse axis of the valve-head 41 which permits use of the pad and new valve in conjunction with the said water-softening system, since the port 17 must be between the ports 16 and 18.

At times when the ports 15 and 16 are in communication with each other through the recess 43 of the valve-head, the latter is then in a position to permit a flow of softened water into the service outlet pipe 21 for use in a dwelling.

Since the port 16, as shown in Figure 10, is connected to the bottom of a tank of the system from which emanates affluent soft water and becomes connected with the port 15, as above described, the soft water, affluent from the softener tank of the system, is thus connected to the service line 21; and at this time the side portion 80 of the surface 42 of the valve-head 41, in conjunction with the pad 42', covers and plugs the drain port 17 so that water does not pass to the drain.

An employment of the pad 42' obviates a need of accurate machining of the surface 42 of the valve-head, and also compensates for a lodging of a few grains of sand between the valve-head and the surface 16.

For certain purposes water under pressure is permitted to enter the port 19 from the chamber 14 of the valve. The water-softening system, not shown, in conjunction with which the valve of the present invention is employed, is such that the brine tank thereof is provided with the conventional valve 90; the arrangement of parts being such that at times when the brine valve 90 is open, the suction generator 26 reduces the level of the brine in the said tank of the system.

At times when there is a flow of water under pressure through the port 19 and in the direction of the arrow 81 (Figure 4), the water becomes forced through the restricted opening 25 and toward the port 18. During a passage of water through the opening 25, a portion of the brine from the brine tank of the system is sucked

through the pipe 82 and into the valve of the present invention, since the liquid which passes through the restricted opening 25 also passes through the passageway 28, thereby providing a suction on the end of the brine pipe 82 for moving brine into the passageway 28, said brine becoming admixed with the liquid under pressure which passes through the opening 25 of the member 26.

Since it is essential at times to back-wash that tank of the system which contains the "Zeolite" crystals, the valve-head of the present invention is caused to be shifted correspondingly by manipulating the lever 68 so that the portion 77 of the lever is caused to engage in the notch 78 for causing the valve-head to span over the ports 17 and 18 for placing said ports in communication with one another. At this time the port 19 is closed by means of the valve-head.

The pipe 13 as above stated is in communication with a source of supply of water under pressure, namely, raw water which enters the chamber 14. At times when the valve-head is in the position shown in Figure 4, the raw water from the chamber 14 is then permitted to flow, under pressure, outwardly of the new valve through the port 15, passageway 20 and service pipe 21 for use as unsoftened raw water.

The port 16 is in communication with the passageway 22 and the pipe 23. The latter is connected to the bottom of the softener tank of the system, namely, the tank containing the "Zeolite" crystals.

The port 17 which is in communication with the pipe 33 through the passageway 32 extends to the drain or sump for a disposal of wash water into a sewer.

The port 18, as above described, is in communication at all times with the port 19 through the aperture 25 of the suction applicator 26, whereby the passageways of the ports 18 and 19 are connected together. Also said port 18 is in communication with the passageway 28, and the latter is in communication with the passageway 82, whereby the port 18 is also in communication with the pipe 82. The latter extends to the top of the brine tank of the system, being provided with the common valve 90.

It will be understood that, as shown by dotted lines in Figure 6, the port 18 is also in communication with the passageway 31, since the latter opens on the passageway 28. The passageway 31 is provided with the opening 35, together with the pipe 36. The latter extends to the top of the softener tank, namely, the tank which contains the "Zeolite" crystals.

In operation, when it is desired to cause softened water to flow to and through the service pipe 21, the operator manipulates the handle 68 for moving the valve-head 41 away from the portion A of the new valve and simultaneously swings the handle 68 to a position whereby the handle engages in the notch 76 (Figure 2), and the recess 43 of the valve-head 41 is then thereby disposed over the openings 15 and 16; and upon the operator then permitting the springs 50 to press the valve-head into position against the portion A, the supply of raw water to the passageway 20 is cut off and softened water permitted to flow through the ports 16 and 15 to the service pipe 21 and from the bottom of the softener tank.

At this time the water under pressure which enters the valve chamber 14 from the pipe 13 flows through said chamber under pressure, outwardly of the valve through either one or both of

the ports 18 and 19 and to the top of the softener tank, through the passageway 37 of the new valve and through the pipe 36.

At this time the water under pressure does not enter the brine tank through the pipe 82 since the conventional valve 90 on the pipe 82, being closed, prevents the same. At times when it is desired to fill the brine tank with liquid, the conventional valve 90 is opened by the operator for the said purpose.

At times when it is desired to back-wash the "Zeolite" crystals within the softener tank of the system, it is necessary to cause a circulation of water through the softener tank in a direction reverse to the normal flow of water therethrough for loosening the debris, scum and the like which clings to the said crystals and before a regeneration of the latter.

For back-washing operation, the operator moves the lever 68 so that it is engaged with the notch 78 (Figure 2), whereby the ports 15 and 16 are opened and the port 19 is closed. At this time since the port 19 is closed, no brine is moved into the new valve through the pipe 82. At this time the valve 90 which governs a flow through the pipe 82 is also closed.

At this time since the port 16 is open, raw water under pressure flows from the chamber 14 through the port 16, passageway 22, pipe 23, to the bottom of the softener tank, up through the bed of "Zeolite" crystals and outwardly of the softener tank, and through the pipe 35, thereby carrying debris with the wash water and into the passageway 37, through the port 18, through the recess 43 of the valve-head 41, through the port 17, the passageway 32 and outwardly of the pipe 33 to the sump or sewer, said flow of wash water being permitted to continue until the "Zeolite" crystals are washed clean and prior to a regeneration of the said crystals.

For regeneration purposes, the operator manipulates the lever 68 so that it is engaged in the notch 77 (Figure 2), whereby the valve-head 41 is then in the position shown in Figure 4 for coupling the ports 16 and 17 together.

The operator now opens the valve 90 for placing the interior of the brine tank in communication with the passageway 28 of the new valve.

At this time raw water under pressure is in the chamber 14 and is flowable outwardly of the service pipe 21 if desired for use in a dwelling. The water under pressure from the chamber 14 causes a flow thereof through the then opened port 19, passageway 24, aperture 25 and into the passageway 28, and from the latter to the passageway 37.

Since the latter is in communication with the pipe 36 and the latter is attached to the top of the water softener tank, water is caused to enter the latter; and in doing so, brine becomes sucked through the pipe 82 from the brine tank and deposited on the crystals in the softener tank. The water which has carried the brine, after passing through the "Zeolite" crystals for regenerating the latter, moves outwardly of the bottom of the softener tank and through the pipe 23. From the latter the water which has deposited its brine in the softener tank enters the passageway 22 and outwardly of the latter to the port 16, enters the recess 43 of the valve-head 41 and becomes switched from the latter through the port 17, passageway 32 to the pipe 33. From the latter the water moves to the sump or sewer.

After a circulation of water-carrying brine

has been occasioned to a suitable extent, the operator then closes the valve 90 and at the time the crystals have been suitably regenerated.

After the operator has closed the conventional valve 90, the valve-head 41 is caused to be shifted so that the recess thereof spans over the ports 15 and 16 which is the normal and operating position of the valve-head for delivering softened water to the service pipe 21.

It is essential that the port of the new valve which is connected to the drain, namely, the port 17, be placed between the ports 16 and 18, as shown in Figure 4, since the port 17 is alternately connected with the top and bottom of the water softener tank of the system, the one connection being for regeneration purposes and the other connection for back-washing purposes.

Among other advantages of the invention it will be seen that an accumulation of debris in the new valve is prevented, since by reason of the particular arrangement of parts water under pressure flows against all interior surfaces of the new mechanism for washing the interior of the valve practically constantly during use.

From the foregoing description, it is thought to be obvious that a water softening system valve constructed in accordance with my invention is particularly adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

40 I claim:

1. In a mixing valve, the combination which comprises a valve body having a plurality of spaced aligned openings providing ports opening into a flat surface with each port communicating with a passage extended through the said valve body and to an external connection thereof, spaced parallel posts mounted on said valve body, a guide plate slidably mounted on said posts, spaced from, aligned with, and parallel to the said flat surface of the valve body, a valve head having a recess in the under surface carried by and slidably mounted on the said guide plate and slidable on the said flat surface, the recess of the said valve head positioned to extend over a plurality of the said ports and the upper part of the said valve head having a gear rack thereon, resilient means on the said posts urging the said guide plate and valve head toward the valve body, a valve bonnet mounted on the said valve body and positioned over the guide plate and valve head, a shaft journaled in the said valve bonnet, a pinion on the said shaft positioned to mesh with the said gear rack of the valve head, and means for rotating the said shaft from the exterior of the valve bonnet for shifting the valve head over the said ports.

2. In a mixing valve, the combination which comprises a valve body having a plurality of spaced aligned ports opening into a flat surface with each port communicating with a passage extended through the valve body, spaced parallel posts extended from the said valve body and positioned at the ends of the said flat surface, 70 a guide plate slidably mounted on said posts,

said guide plate spaced from, aligned with and parallel to the said flat surface of the valve body, a valve head having a recess in the under surface carried by and slidably mounted on the said guide plate and slideable on the said flat surface of the valve body, said valve head having a gear rack thereon and the recess in the under surface thereof positioned to extend over a plurality of the said ports, resilient means on the said posts for urging the guide plate and valve head toward the valve body, a valve bonnet mounted on the valve body and positioned over the guide plate and valve head, a shaft journaled in the said valve bonnet, a pinion on the shaft positioned to mesh with the gear rack of the valve head, a handle pivotally mounted on the outer end of the said shaft for rotating the shaft, and means spacing the valve head from the said flat surface by the handle through the shaft and guide plate.

3. In a mixing valve, the combination which comprises a valve body having a plurality of spaced aligned ports opening into a flat surface with each port communicating with a passage extended through the valve body, one of said passages having a venturi therein for providing suction to draw a product into the valve, spaced parallel posts extended from the said valve body and positioned at the ends of the said flat surface, a guide plate slidably mounted on the said guide posts, said guide plate spaced from, aligned with and parallel to the said flat surface of the valve body, a valve head having a recess in the under surface carried by and slidably mounted on the said guide plate and slideable on the said

35

flat surface of the valve body, a filler pad carried by the said valve head and positioned between the valve head and flat surface, said valve head having a gear rack thereon and the recess in the under surface thereof positioned to extend over a plurality of the said ports, resilient means on the said posts for urging the guide plate and valve head toward the valve body, a valve bonnet mounted on the valve body and positioned to cover the guide plate and valve head, a shaft journaled in the said valve bonnet, a pinion on the shaft positioned to mesh with the gear rack of the valve head, and a handle pivotally mounted on the outer end of the shaft for rotating the shaft to shift the said valve head over the ports of the said flat surface of the valve body.

RALPH D. ZIMMERMAN.
